SURSINGLE HANDLE

James D. Houston, 5528 N. 50th Ave.,
Omaha, Nebr. 68104

Filed Mar. 13, 1967, Ser. No. 6,209

Term of patent 14 years

(Cl. D30—19)

FIG. 1 is a perspective view of a sursingle handle, the broken line showing of the sursingle being disclosed for illustrative purposes only;

FIG. 2 is another perspective view of the sursingle handle, showing the opposite side thereof; and

FIG. 3 is a sectional view, taken on the line 3—3 of FIG. 2, looking in the direction indicated by the arrows, to show the shape of the sursingle handle.

The lower faces of the handle are substantially plain.

I claim:

The ornamental design for a sursingle handle, as shown and described.
